(57) **CLAIM**

The ornamental design for a folding snow shovel as shown and described.

DESCRIPTION

FIG. 1 is a front perspective view of a folding snow shovel showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a right side view of the folding snow shovel shown in another configuration;

FIG. 10 is a front perspective view thereof; and,

FIG. 11 is a rear perspective view thereof.

The broken lines in the figures depict portions of the folding snow shovel that form no part of the claimed design.

1 Claim, 10 Drawing Sheets
